No. 649,882.

Patented May 15, 1900.

R. P. WEED.

ATTACHMENT FOR PUMP RODS.

(Application filed Sept. 1, 1899.)

(No Model.)

UNITED STATES PATENT OFFICE.

ROYAL P. WEED, OF LANARK, ILLINOIS.

ATTACHMENT FOR PUMP-RODS.

SPECIFICATION forming part of Letters Patent No. 649,882, dated May 15, 1900.

Application filed September 1, 1899. Serial No. 729,191. (No model.)

To all whom it may concern:

Be it known that I, ROYAL P. WEED, a citizen of the United States of America, residing at Lanark, in the county of Carroll and State 5 of Illinois, have invented certain new and useful Improvements in Attachments for Pump-Rods, of which the following is a specification.

My invention relates to certain improvements in attachments for pump-rods, the object of which is to relieve the pump and the driving mechanism from the great strain caused by the effort to start the column of water upon the upstroke. It is particularly valuable in connection with windmills and 15 has been used most extensively for that purpose.

The drawings illustrate the preferred construction, showing a side elevation in Figure 1, a central vertical section in line 2 2 of Fig. 20 1 in Fig. 2, a similar section at right angles thereto in Fig. 3, a horizontal section looking downward from the line 4 4 of Fig. 1 in Fig. 4, a similar section in line 5 5 of the same figure in Fig. 5, a side elevation of the detail in Fig. 6, 25 and a similar elevation of a part thereof in Fig. 7.

In the drawings, A is the windmill-rod, and B the pump-rod. The pump-rod is provided with a downward extension C, composed of 30 two parts c c', secured upon opposite sides of the windmill-rod by means of bolts c² c³ and extending below the rod in the form of a yoke c⁴, terminating at the bottom in a horizontal disk-shaped plate c⁵, formed by the union of 35 the two parts c c' by means of bolts c⁶ c⁷. In this housing is arranged a coiled spring D, its lower end resting upon the plate c⁵, and a sliding block E is guided vertically at its upper end e in a socket c⁸ and extends at its 40 lower end through an opening c⁹ in the disk-shaped plate c⁵. A projecting ear or rib e' rests upon the top of the spring D, and a similar rib e² acts as a stop to check the downward movement of the block in the yoke by 45 striking against the disk-shaped plate c⁵. The block E is made in the shape of a trough bridged at the bottom e³ to receive the pump-

rod B. A pin e⁴ is let into the block to engage the pump-rod, said pin being forced inward by a flat spring e⁵, secured to the block at e⁶. 50 The block is provided with a socket e⁷ and a perforated ear e⁸, furnishing a bearing for a key, having a spindle f fitted to the ear and bearing a wing f', arranged behind the spring, and a handle f², in convenient position for manipulation. By drawing the handle forward in Fig. 6 the spring is lifted to withdraw the coupling-pin e⁴ from the pump-rod. A rivet e⁹ furnishes a stop to limit the movements of the key in this direction, sufficient movement 55 being permitted to enable the wing to swing past the dead-center, so as to lock the spring in an open position.

I do not limit myself to the exact construction herein shown and described, as considerable variation is possible without departing from the principle of the invention.

I claim as new and desire to secure by Letters Patent—

1. The combination with the yoke, C, made 70 up of the two pieces, c, c', adapted to be attached to opposite sides of the windmill-rod and terminating at the bottom in a disk-shaped plate, c⁵, formed by securing the two pieces together at c⁶, c⁷, of the trough-shaped 75 block, E, guided in the yoke and provided with a shoulder and the spring, D, interposed between the disk-shaped plate and said shoulder; substantially as described.

2. The combination with the yoke, C, of 80 the spring, D, supported therein, the block, E, guided in the yoke and bearing the ribs, e', e², the former resting upon the top of the spring and the latter arranged to engage the yoke and limit the movement of the block with 85 respect thereto; substantially as described.

In witness whereof I have hereunto set my hand, at Lanark, in the county of Carroll and State of Illinois, this 15th day of August, A. D. 1899.

ROYAL P. WEED.

Witnesses:

B. F. PUTERBAUGH,
GEO. W. REDLINE.
